UNITED STATES PATENT OFFICE.

PERCY B. BALL, OF PROVIDENCE, RHODE ISLAND, ASSIGNOR TO FAHYS WATCH CASE COMPANY, OF NEW YORK, N. Y., A CORPORATION OF NEW YORK.

DESIGN FOR A HANDLE FOR SPOONS OR FORKS.

SPECIFICATION forming part of Design No. 36,420, dated July 14, 1903.

Application filed April 24, 1903. Serial No. 154,189. Term of patent 3½ years.

To all whom it may concern:

Be it known that I, PERCY B. BALL, a citizen of the United States, and a resident of Providence, in the county of Providence and State of Rhode Island, have invented and produced a certain new, original, and ornamental Design for a Handle for Spoons or Forks, of which the following is a specification.

In the accompanying drawings, Figure 1 shows the obverse side of a handle for a spoon or fork having my design applied thereto, and Fig. 2 the reverse side of the handle.

What I claim is—

The ornamental design for a handle for spoons or forks, substantially as shown.

Signed at Providence, in the county of Providence and State of Rhode Island, this 21st day of April, A. D. 1903.

PERCY B. BALL.
